VALVE OPERATING MECHANISM

Vilynn O. Beam, Toledo, Ohio, assignor, by mesne assignments, to Minneapolis-Honeywell Regulator Company, Minneapolis, Minn., a corporation of Delaware

Application March 14, 1932, Serial No. 598,575

9 Claims. (Cl. 137—139)

This invention relates to improvements in valve operating mechanism embodying a prime mover for opening valves which automatically tend to close when power to the prime mover is cut off.

5 The present invention has among its objects to provide a valve operating mechanism for valves of the character indicated which shall be relatively simple in construction, reliable in operation and otherwise well adapted for its intended purpose.

Referring to the drawings wherein the preferred form of the invention is shown,—

Fig. 1 is a vertical section through the improved valve operating mechanism, the view being taken on line 1—1 of Fig. 2;

Fig. 2 is a vertical section on line 2—2 of Fig. 1;

Fig. 3 is a plan view of the valve operating mechanism, the cover being removed and parts being broken away to more clearly show the construction;

Fig. 4 is a vertical section on line 4—4 of Fig. 2;

Fig. 5 is a view showing the position of certain parts of the valve operating mechanism when the valve is held open by a manually operable latch;

Fig. 6 is a perspective view of the switch mechanism forming part of the valve operating mechanism;

Fig. 7 is an electrical diagram of the circuits for operating certain parts of the valve operating mechanism, and

Fig. 8 shows the environment where the improved valve operating mechanism has special utility, namely, in connection with gas burning apparatus.

In the drawings, 9 indicates a valve casing wherein is positioned a valve 10 which is normally held to its seat by a spring 11 the upper end of which bears against a closure plate 12 secured to said casing by a collar nut 13. Coupled to the valve 10 is a stem 14 which slidably extends through the plate 12. Supported by the plate 12 is a bowl 15 across the top of which extends a leather diaphragm 16 and through which latter the stem 14 extends in a gas tight manner, the diaphragm serving as a seal against the escape from the bowl 15 of such gas as may leak past the stem 14 where it passes through the plate 12. A ring 17 clamps the diaphragm to the top flange of said bowl. Supported by and extending upwardly from the bowl 16 are two plates or standards 18 arranged in parallel spaced relation.

Extending between the plates 18 at one side thereof is a rod 19 on which is pivotally supported a lever 20 which is pivotally connected to the

upper end of the valve stem 14 as by a yoke 21. Extending between said plates in vertically spaced relation are non-rotatable shafts or rods 22 and 23. Turnably mounted on the rod 22 is a lever arm 24, and connecting the latter with the lever 20 is a link 25.

Rotatably mounted on the rod 22 is a gear wheel 26. Projecting from one side of said wheel is a crank pin 27 of a length to extend across the path of movement of said arm 24 as clearly shown in Figs. 2 and 3. Consequently when said wheel is turned in a clock-wise direction as viewed in Fig. 1, said pin 27 will engage said arm from below and turn it about the rod 22, and as a consequence of such turning the arm will turn the lever 20 in a direction to elevate the valve stem 14 whereby to open the valve 10 against the tension of the spring 11.

Rotatably mounted on the rod 23 is a sleeve 28 to which are non-rotatably secured a pinion 29 and a gear wheel 30, the former meshing with the gear wheel 26. Rotatably mounted on the rod 22 is a pinion 31 which meshes with the gear wheel 30 and coupled to the pinion 31 for rotation therewith is a gear wheel 32. In mesh with the gear wheel 32 is a pinion 33 non-rotatably secured to the armature shaft 34 of an electric motor M, the armature of which is rotatable between pole pieces 35, the electrical winding for which is indicated at 36. The motor pole pieces 35 are supported by supports 37 and 38 which extend from one of the standards 18. From the foregoing it will be understood that the gear wheel 26 is rotated by the motor pinion 33 in a direction to open the valve.

Mounted on the motor shaft 34 for rotation therewith is a brake disk 39. Turnably mounted on the support 38 is a bell crank, (see Fig. 4) one arm 40 of which carries a brake shoe 41 for engaging with the brake disk 39. The other arm 42 of said bell crank has secured thereto a resilient extension 43 which pivotally supports an armature shoe 44. A light spring 45 normally keeps the brake shoe 41 out of contact with the brake disk 39.

Supported by a bracket 46 secured to plate 18 in an electro magnet generally indicated at 47, the electrical winding for which is indicated at 48. When the electro-magnet is energized the armature shoe 44 is attracted to it with the result that the bell crank to which said shoe is attached is actuated and the brake 41 applied to the disk 39.

Extending between the plates 18 and supported thereby is a block 50 (Figs. 1 and 6) of insulat-

35

45

50

55

ing material such as hard rubber. Supported by said block and extending therefrom is a rigid switch element 51 having laterally extending contact points 52 and 53. Also secured to said block are two resilient switch elements or blades 54 and 55, the blade 55 extending below its contact 52 and blade 54 extending above its contact 53. Blade 55 is normally open with respect to its contact 52 and blade 54 is normally closed with respect to its contact 53.

The blade 54 is adapted to be opened with respect to its contact 53 by a finger 56 formed as an extension of the link 25 which connects the lever arm 24 and lever 20. The blade 55 is adapted to be closed with respect to its contact 52 by an arm 57 of a latch lever 58 turnably mounted on a pin 63 supported by one of the plates 18. A push button 60 mounted in a side wall of the cover 61 is adapted to actuate the latch lever 58.

The lower end of the latch lever 58 is hooked or notched as indicated at 62 in a manner to engage a pin 63 carried by the lever 20, said pin being shown as the pin which connects the lever 20 and the link 25. The latch lever 58 has utility when it is desired to manually open the valve 10 by the lever 20, as in the event of current failure to the motor M. After the valve has been opened manually as said, the push button 60 is pressed to bring the hooked end 62 of the latch lever 58 below the pin 63 whereby to hold the valve open until released either manually or automatically as when power for the motor M is again available, as will more fully appear hereinafter. Fig. 5 shows the position of the parts when the latch 58 is in position to hold the valve open, it being noted that the arm 57 of said latch engages the switch blade 55 in a manner to hold the latter against its contact 52 and that the finger 56 does not engage the switch blade 54 and consequently the latter remains closed. The power wires, not shown, pass through an opening 64 in the top flange of the bowl 15 and are secured to binding posts 65 carried by an insulating panel 66 supported by brackets 67 secured to one of the upright standards 18. The switch elements 51, 54 and 55 are appropriately connected by wires, not shown, to the binding posts 65 and to the motor winding 36 and electro magnet winding 48.

As shown in the electrical diagram in Fig. 7, a low voltage circuit is used for operating the motor M and electro magnet 47, the main line voltage being stepped down by a transformer T. The motor winding 36 and electro magnet winding 48 are in series with a room thermostat RT which is the prime controller for actuating the valve operating mechanism. The switch 54 is part of a by-pass circuit around the magnet winding 48, the switch being closed when the valve 10 is closed. The switch 55 is normally open and is closed only when the valve 10 is held open by the latch 58 in which event the room thermostat is shorted out of the motor and magnet circuits.

When the room thermostat calls for heat it moves to the left as viewed in Fig. 7. Current thereupon flows through the motor winding 36 and through the room thermostat by way of the circuit containing the switch 54, the electro magnet 48 being by-passed for the time being. Shortly before the motor M has fully opened the valve, the switch 54 will be opened by the finger 56 and thereupon the current will flow through the electro-magnet winding 48 with the result that the armature 44 is attracted and the brake 41 applied to the brake disk 39 with the result that the

valve 10 is held open against the tension of the valve spring 11.

When the switch 54 is opened to place the motor winding 36, the magnet winding 48 and the room thermostat in series, the magnet winding 48 offers such resistance to the flow of current that the motor winding 36 does not receive sufficient current to cause rotation of the motor. When the room thermostat moves to the right, as when there is no call for heat, the circuit to the magnet winding 48 is broken with consequent release of the brake 41 whereupon the valve spring 11 closes the valve,—it being understood that the gear train is such as will permit the spring to rotate the gear trains in closing the valve.

Assuming now that current is not available to open the valve when the room thermostat calls for heat. The valve may then be opened by hand by the lever 20 and latched in open position by the latch 58 as already explained. In latching the valve open, the switch 55 is closed by the latch arm 57. Referring to Fig. 5, it will be noted the finger 56 does not open the switch 54 when the valve is latched in open position and it will therefore be understood that while for practical purposes the valve 10 is substantially fully open when the latch 58 is engaged with the pin 63, nevertheless, the lever 20 and parts associated therewith may be moved by the gear wheel 26 a sufficient additional distance to permit the finger 56 to open the switch 54.

Assuming now that current becomes available while the latch 58 is in engagement with the pin 63 on the lever 20. Since both switches 54 and 55 are closed, with the result that the electro-magnet winding 48 and the room thermostat are by-passed, current will flow direct to the motor winding 36 with the result that the motor will rotate in a valve opening direction and lift the pin 63 away from the latch 58 whereupon the latter will automatically swing to the position shown in Fig. 1 with consequent opening of the switch 55. In this connection it may be noted that the switch 55 being a spring blade will tend to open and in so doing moves the latch into the position shown in Fig. 1. The switch 55 will be opened as said, before the finger 56 opens the switch 54. If the room thermostat is closed the motor will continue to operate until the finger 56 has opened the switch 54 whereupon the current passes through the magnet winding 48 with consequent application of the brake 41 and the throttling of power to the motor M to such degree that for practical purposes the motor is deenergized even though the winding 36 is in series with the winding 48 of the electro-magnet. In case the room thermostat should be in open or in no-call-for heat position when current becomes available, the motor will be momentarily energized since the circuit is through the closed switches 54 and 55, but as soon as the switch 55 is opened by release of the latch 58, the motor circuit will be broken and consequently the valve will automatically close under the tension of the valve spring 11.

It will of course be understood that the valve in closing will impart rotation to the gear train to which the rotary motor is connected, such rotation being due to the downward force exerted by the arm 24 on the crank pin 27. Since the arm 24 and crank pin 27 are not interconnected there will be no sudden stopping of the gear train, the latter being free to continue its rotation without any effect on the valve, such rotation usually ceasing before the crank pin 27 reaches the top side of the arm 24. There being no sudden stopping

of the gear train when the valve comes to its seat, there will of course be no rebound or sudden reversal of movement of the parts tending to lift the valve from its seat.

5. Referring to Fig. 8, the valve operating mechanism is shown as controlling the admission of gas to a gas burning apparatus of a well known type having a secondary air damper D, the lever 20 being shown as coupled by a spring S to the 10 damper for opening and closing the damper as the valve is opened and closed.

What I claim is:

1. Mechanism for operating a valve biased toward closed position comprising in combination 15 with such valve, a wheel crank, an arm turnable on the same axis as said wheel and extending radially therefrom across the path of travel of the crank, means for simultaneously actuating the valve and the said arm independently of the 20 wheel crank, and means including a rotary motor operable to drive the wheel crank in one direction only.

2. Mechanism for operating a valve biased toward closed position comprising in combination 25 with such valve, a crank, means including a rotary motor operable to drive the crank in one direction only, a pivoted arm disconnected from but extending across the path of travel of said crank in such a manner that the crank may 30 revolve a substantial part of one revolution before engaging with said arm, and means operable by said arm for opening said valve against its bias when the arm is turned by the said crank, the bias of said valve being sufficient to close said valve 35 and cause the arm to rotate the crank and motor in reverse direction.

3. Mechanism for operating a valve biased toward closed position comprising in combination 40 with such valve, a crank, means including a rotary motor operable to drive the crank in one direction only, a pivoted arm disconnected from but extending across the path of travel of said crank in such a manner that the crank may revolve a substantial part of one revolution before engaging 45 with said arm, means operable by said arm for opening said valve against its bias when the arm is turned by the said crank, the bias of said valve being sufficient to close the valve and cause the arm to rotate the crank and motor in reverse 50 direction, and manually operable means adapted to coact with the last named means for holding the valve open.

4. Mechanism for operating a valve comprising in combination, a valve, a crank, means including 55 a rotary motor operable to drive the crank in one direction only, a pivoted arm disconnected from but extending across the path of travel of said crank in such a manner that the crank may revolve a substantial part of one revolution before engaging 60 with said arm, a lever coupled to said valve, a link connecting the arm and lever whereby the arm when turned by the crank may open said valve, and a spring biasing the valve to closed position and having sufficient power to cause said arm to rotate the crank and motor in reverse direction.

5. Mechanism for operating a valve biased toward closed position comprising in combination 65 with such valve, a crank, means including a rotary motor operable to drive the crank in one di-

rection only, a pivoted arm disconnected from but extending across the path of travel of said crank in such a manner that the crank may revolve a substantial part of one revolution before engaging with said arm, means operable by said 5 arm for opening said valve when the arm is turned by said crank and power-operated means controlled by the last named means for relieving the said motor from holding the said valve open.

6. In combination, a valve biased to one of its 10 controlling positions, a motor operable to drive in only one direction, a pivoted member positively connected to said motor, an arm pivoted concentrically with said pivoted member and arranged to be engaged and rotated by said member when 15 driven by the motor, and connections between the arm and valve operative to move the valve to its other controlling position when the arm is rotated by said member, the bias of said valve being sufficient to return the valve to its first-mentioned 20 controlling position and simultaneously to rotate the motor and pivoted member in the reverse direction.

7. In combination, a valve, motor means arranged to open the valve when energized and 25 close the valve when deenergized, connections between the motor means and valve including a pivoted cross-arm, a circuit for energizing the motor means, a manually operable member pivoted intermediate its ends, one end of said member being arranged to latch the cross-arm in a position wherein said valve is partially open when the valve is manually operated and the pivoted member manually manipulated, a switch arranged to be closed by the other end of said member when 35 manipulated to valve latching position, and an independent circuit for the motor means controlled by said switch.

8. In combination, a valve biased to closed position, motor means arranged to open the valve 40 when energized and maintain the same in open position against its bias, connections between the motor means and valve including a connecting link, switching means arranged to be operated by said connecting link, and circuit connections 45 between the switching means and motor means arranged selectively to energize one portion of the motor means to open the valve or to energize another portion thereof to hold the valve open upon operation of the switching means. 50

9. In combination, a valve biased to closed position, a valve stem connected to the valve, a pivoted cross-arm connected to the valve stem, a link connected to the cross-arm, a rotary electrical motor connected to said link and operative 55 to open the valve against its bias through the link, cross-arm, and valve stem when energized, an electro-magnet arranged to hold the valve open against its bias, two-position switching means located in the path of movement of said 60 link and arranged to be moved from a first position to a second position when the link is moved to valve open position, a circuit for operatively energizing the motor controlled by the switching means in its first position, a circuit for operatively 65 energizing the electro-magnet controlled by the switching means when in its second position, and a main control switch dominating both said circuits.
